MAGIC TRICK

Kenneth S. Franke, Woodside, Long Island, N. Y.;
 Marian Franke, executrix of said Kenneth S.
 Franke, deceased

Application July 25, 1946, Serial No. 686,089

7 Claims. (Cl. 272—8)

1

This invention relates to magic tricks and more particularly to a "devination" trick in which any one of a plurality of apparently identical objects selected by a spectator without the knowledge of the "magician" can be identified by him without the necessity of his seeing the object.

In accordance with the invention, a plurality of objects identical in outward shape and size, but each having a distinct visible marking, are provided and handed to a spectator together with a small container such as a cloth bag. For purposes of illustration it is assumed that three objects in the shape of elongated solid cylinders or "pillars" are provided, each having a different color. The spectator is requested to select one of the objects while the magician turns his back and to place the selected object in the bag, which is then handed to the magician. The latter holds the bag containing the object behind his back and then announces to the spectator the color of the object which he had selected. All but one of the objects are provided with indentations or holes extending into the objects from one end and the hole in each object is of a distinct length. It is preferred that the holes extend longitudinally into the objects from one end and that each object has affixed thereto, over the opening to the hole, a small cover of a fabric material such as felt. The fabric serves to cover the opening to the hole so that the holes are not perceived by the spectator. It is also preferred that the ends of the objects or pillars opposite the felt covers be slightly indented for a reason to be explained hereinafter. Unbeknown to the spectator the magician has concealed in his hand or clothing a pointed instrument such as a needle or pin and presses the needle into the covered end of the selected object so that it enters the hole therein. The magician can tell by the depth of penetration of the needle whether the selected object is, for example, the red one, the yellow one or one of some other color.

For a better understanding of the invention reference may be had to the accompanying drawing in which:

Figure 1 is an isometric vertical elevation of three pillars one end of each pillar being of a different color;

Figure 2 is a view similar to Figure 1 but with the lower portion of the pillars broken away to show the concealed holes therein;

Figure 3 is a vertical sectional view of a needle or pin within a carrying case; and

Figure 4 is a vertical elevation showing one of

2

the objects or pillars within a cloth bag and with the needle inserted into the hole in the pillar.

Referring to Figure 1 of the drawing three objects 10 shown in the form of small "pillars" are illustrated, these objects having identical outward shapes and sizes. The upper end of each pillar is preferably slightly indented as at 12 and the inner portion of the indentation is colored differently for each pillar. As shown in Figure 10, 2, two of the pillars are provided with indentations or holes 14 extending into the pillars from the lower ends. As shown, the hole in the center pillar is shorter than the hole in the right hand pillar and the left hand pillar is not provided with any hole or indentation corresponding to the holes 14. The lower end of each pillar has affixed thereto a disc 16 of a fabric material such as felt, these fabric discs serving to conceal the openings to the holes 14.

20. In Figure 3 is shown a needle or pin 18 having a small knob or handle 20 secured to one end, the knob being adapted to have a friction fit within a container 22. The container 22 is provided in order to prevent damage from the needle while 25 the device is not being used.

A small bag 24 preferably of suitable cloth is shown in Figure 4 the opening in which may be closed as by means of a rubber band 26.

In demonstrating the trick, the three pillars 30 as shown in Figure 1, together with the bag 24, are handed to the spectator who is requested to select one of the pillars, to remember the color thereof and to place the selected pillar within the bag which is then closed by means of the 35 rubber band 26. The bag containing the selected pillar is then handed to the magician who places it behind his back. Due to the indentation 12 the magician can readily feel the pillar through the bag and tell which end is indented and therefore by which end has the covering 16. He then removes the needle 18, which he may have previously pinned underneath his jacket or concealed in his hand and presses the needle through the bag 24 and the covering 16. If the needle does not penetrate farther than through the thickness of the covering 16, the magician would then know that the selected object is the one shown at the left in Figures 1 and 2 and he would then announce that the spectator had selected, for instance the pillar having the red end. If, however, the needle passes through the covering 16 into a hole 14 the magician immediately knows by the depth through which the needle penetrates whether the object is the one having the short hole as shown at the center in Figure 2, or the

one having the long hole as shown at the right in that figure. The magician then removes the needle and conceals it again in his clothing or in his hand and hands the still closed bag 24 back to the spectator for examination.

Although three objects have been shown and described it is believed apparent that any suitable number can be used, it merely being necessary for the magician to have memorized the association of the different colors with the different lengths of the holes corresponding to the colors. It is also believed obvious that instead of providing the objects in the shape of pillars as shown, these objects can take any suitable form or shape as long as they are all of identical outward shape and size. For example, the objects may take the form of small doll figures, the holes 14 extending into the figures through the feet which would be covered with the fabric 16. Although the bag 24 adds considerably to the effect of the trick it is not necessary that it be used. In other words, a selected object can be handed directly to the magician behind his back so that he can not see the identifying color. He then proceeds to push the needle into the object as described above and then announces the identity thereof. It is not necessary that different colors be used since any suitable marks of identification can be used satisfactorily. For example, the objects may be numbered or lettered in a manner such that the mark will be visible but not discernible by touch.

Although one of the pillars has been shown and described as not being provided with a hole 14, it is understood that, if desired, each pillar or object may be provided with a hole, it merely being essential that all of the holes be of different lengths or depths, and that the magician have memorized the relation between the length of each hole and the corresponding markings on the pillars. Instead of indenting the ends of the pillars as shown at 12, the ends opposite the ends covered by the fabric 16 can be beveled or provided with any other shape so that one can distinguish between the ends while a pillar is within the bag 24. In place of the cloth bag 24, other containers such, for instance, as paper envelopes can be used, the main advantage of the cloth residing in the fact that the small puncture made by the needle 18 will not be discernible to the spectator.

Obviously many other modifications and variations of the invention as above set forth may be made without departing from the spirit and scope thereof, and therefore only such limitations should be imposed as are indicated in the appended claims.

I claim:

1. A magic trick device comprising a plurality of objects of substantially identical outward shape and size, certain of said objects being provided with indentations of different depths, means covering the openings to said indentations so that they are not visible to the eye and means for determining the depth of an indentation comprising a pointed instrument adapted to penetrate said cover means and to enter one of the objects to the bottom of its indentation, the amount of penetration serving as an indication of the depth of the indentation and thus of the identity of the object penetrated.

2. A magic trick device comprising a plurality of objects of substantially identical outward shape and size, each object having a different visible marking and certain of said objects being

provided with indentations, a cover of fabric material over the outer end of each indentation, so that the indentations are not visible to the eye, and means for determining the depth of an indentation comprising a pointed instrument

adapted to penetrate said fabric cover and to enter one of the objects to the bottom of its indentation, the amount of penetration serving as an indication of the depth of the indentation and thus of the identity of the object penetrated.

3. A magic trick apparatus comprising a plurality of objects of substantially identical outward shape and size, each of said objects being marked so that it can be visibly identified and certain of said objects being provided with indentations of different depths, cover means for said indentations so that the indentations are not visible to the eye, a closable container into which one of said objects can be placed, and means for determining which one of the objects has been placed in the container comprising a pointed instrument adapted to penetrate said container and said cover means and to enter the object in the container to the bottom of its indentation, the amount of penetration serving as an indication of the depth of the indentation and thus of the identity of the object within the container.

4. A magic trick device comprising a plurality of objects of substantially identical outward shape and size, each object having a different visible marking and each but one of said objects being provided with an indentation extending into the object from one side and having a certain depth and the depths of the indentations being different for each of the objects, means covering the opening to each indentation so that it is not outwardly visible, and means for determining the depth of an indentation and thus the identity of the object containing that indentation comprising a pointed instrument adapted to be pushed through the said cover means to the inner end of the indentation, the amount of penetration of said instrument providing an indication of the depth of the indentation and therefore the identity of the object.

5. A magic trick device for magicians comprising a plurality of objects of substantially identical outward shape and size, each object having a different visible marking and each but one of said objects being provided with an indentation extending into the object from one side and having a depth known to the magician to correspond to one of said markings, means covering the opening to each indentation so that it is not outwardly visible, and means whereby the magician can determine the identity of one of the objects handed him by a spectator, comprising a pointed instrument adapted to be pushed through the said cover means to the inner end of the indentation in that object, the amount of penetration of said instrument providing the magician with an indication of the depth of the indentation and therefore the identity of the object.

6. A magic trick device for magicians comprising a plurality of elongated objects of substantially identical outward shape and size, one end of each object being marked with a different color and the opposite end of each but one of said objects being provided with an indentation extending into the object from that end and having a depth known to the magician to correspond with the color marking on the other end of the same object, means covering the opening to each indentation so that it is not outwardly visible to a spectator, and means whereby the magician can

determine the depth of an indentation and thus the identity of the object containing that indentation comprising a pointed instrument adapted to be pushed through the said cover means to the inner end of the indentation, the amount of penetration of said instrument providing an indication of the depth of the indentation and therefore the identity of the object.

7. A magic trick apparatus for magicians comprising a plurality of objects of substantially identical outward shape and size, each object having a different visible marking and each but one of said objects being provided with an indentation extending into the object from one side and having a depth known to the magician to correspond to one of said markings, means covering the opening to each indentation so that

it is not outwardly visible to the spectator, a closable container of fabric material into which one of said objects can be placed by the spectator, and means whereby the magician can subsequently determine which one of the objects has been placed in the container comprising a pointed instrument adapted to be pushed through said container and the said cover means to the inner end of the indentation in the object in the container, the amount of penetration of said instrument providing an indication to the magician of the depth of the indentation and therefore the identity of the object in the container.
